UNITED STATES PATENT AND TRADEMARK OFFICE
Certificate

Patent No. D. 648,038 S

Patented: November 1, 2011

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Michel Gaudreau, Québec (CA); Louis-André Gaudreau, Québec (CA); François Bouchard, Québec (CA); Mathieu Piché, Québec (CA); and Martin Forget, Québec (CA).

Signed and Sealed this Twenty-fifth Day of June 2013.
